UNITED STATES PATENT OFFICE.

FREDERICK RICHARD SIMMS, OF LONDON, ENGLAND, ASSIGNOR TO THE SIMMS MAGNETO COMPANY, OF BLOOMFIELD, NEW JERSEY, A CORPORATION OF NEW YORK.

MAGNETO-ELECTRIC MACHINE FOR COMBINED IGNITION AND ILLUMINATING PURPOSES.

1,198,072.

Specification of Letters Patent. Patented Sept. 12, 1916.

Application filed July 21, 1913. Serial No. 780,376.

To all whom it may concern:

Be it known that I, FREDERICK RICHARD SIMMS, a subject of the King of Great Britain, residing at 6 Charles street, Berkeley Square, London, England, have invented new and useful Improvements in Magneto-Electric Machines for Combined Ignition and Illuminating Purposes, of which the following is a specification.

10 This invention relates to magneto-electric machines for generating ignition and illuminating current such as is required, for example, in the case of motor road vehicles.

In the specification of former British Patent No. 19122 of August 25, 1911 there is described a magneto-electric machine of this class in which a pair of armatures is employed which rotate between two pairs of pole-pieces, one of these armatures being designed to generate current for the ignition of the explosive charge of an internal combustion engine, while the other is utilized for generating current for supplying the head and other lamps of the vehicle to which 25 the gear is fitted.

Now, the object of the present invention is to improve the construction of machines of this type chiefly in the direction of the reduction of their weight and dimensions, 30 and at the same time a more powerful motor is produced for starting an internal combustion engine than the permanent magnet type of motor.

To this end according to the invention, in 35 lieu of providing a set of permanent magnets for furnishing the magnetic fields for both the lighting and ignition armatures, I now make use of permanent magnets for providing the field for the ignition armature only, that for the lighting armature being provided by one or more electro-magnets.

In a suitable arrangement for carrying out the invention I provide a pair of straight electro-magnets, the cores of which are arranged parallel to one another, and either side and near the top of the permanent magnet which provides the magnetic field for the ignition armature. The cores of these electro-magnets are mounted in side plates, 45 the lower extremities of which are formed as pole-pieces, between which the lighting armature rotates. These pole-pieces are arranged at a point above the level of the pole-

pieces of the permanent magnet between which the ignition armature rotates, but, in practice, the side plates may be extended below the latter pole-pieces for structural purposes, it being understood, however, that the arrangement is such that the field of the electromagnet is wholly or mainly insulated 55 from the field of the permanent magnet; for example, the said extension may be in the form of wings at the ends only of the side plates, and adjacent to the ends of the pole-pieces of the permanent magnet, gaps being 60 provided between the said pole-pieces and the extensions which themselves are made with central holes or gaps.

In a modified construction of machine I make use of a single coil electro-magnet instead of the pair of coils as above described, and it will be understood that the permanent magnet may be either of a horse-shoe shape, in which event it embraces the electro-magnets, or in the form of two bar-magnets, 70 connected together at the upper end by a transverse pin or the like.

To enable my invention to be fully understood I will describe it by reference to the accompanying drawing, in which:—

Figure 1 is a side view of one form of magneto-electric machine constructed according to the invention. Fig. 2 is a sectional view thereof. Fig. 3 is a side view of a modified form of the machine, and Fig. 4 is a sectional end view illustrating a further modification.

Referring first to the construction illustrated in Figs. 1 and 2, *a* are two straight electro-magnets having the cores *b*, which cores are arranged parallel to one another, and *c*, *c* are the side plates in which the cores *b* are mounted and the lower extremities of which are formed as the pole-pieces or shoes *d* between which the lighting armature *A* is designed to rotate.

e is the permanent magnet which, in the arrangement under consideration, is in the form of a horse-shoe magnet, the upper or yoke end of which embraces the electro-magnets *a*. At its lower end the permanent magnet *e* carries the pole-shoes or pieces *f* between which the ignition armature *B* rotates. The pole-pieces *d* for the lighting armature *A* are arranged just above the 105 pole-pieces *f* for the ignition armature *B*, the

side plates *c*, to which the former pole-shoes are attached, being extended downwardly at the sides as indicated at *c*¹ for structural purposes; the said lateral extensions *c*¹, however, are separated by the slots or gaps *g* from the pole-pieces *f*, in order to insulate the magnetic flux of the lighting field from the field of the permanent magnet.

In the embodiment of my invention herein illustrated I have shown cores *b* of the magnet coils each provided at one end with a threaded portion *b*¹ indicated in dotted lines in Fig. 2, which is screwed into one of the side plates *c*, while the other end of the core *b* is provided with a reduced portion *b*², which extends through an aperture in the other side plate to which it is connected by means of the flat head screw *b*³. I have also shown the pole pieces *d*, *d* for the lighting armature *A*, which in this instance are formed integral with the side plates *c*, as supported upon the pole pieces *f* for the ignition armature *B* and connected thereto against accidental displacement by dowel pins *d*¹. It is to be understood that the slots *g* which I employ for the purpose of insulating the pole pieces *d* from the pole pieces *f* do not totally insulate them therefrom. The provision of such slots, however, is sufficient to insure a sufficient independence of the magnetic fields of the two pairs of pole pieces or pole shoes, and the length of the slots is determined by the speed at which the armatures are to be run. In some cases in practice, these magneto machines are driven direct from the engine shaft and consequently at engine speed, while in other cases they are driven at a higher speed and the slots will be made of sufficient extent to accomplish the desired result.

In the modified form of machine illustrated in Fig. 3, only one electro-magnet *a* is made use of, which magnet is embraced as in the preceding construction by the permanent magnet *e*. In other respects this form of machine is similar to that illustrated in Figs. 1 and 2.

Fig. 4 illustrates the construction of the machine in which the horse-shoe magnet *e* is dispensed with and in lieu thereof there is employed a pair of bar-magnets *h*. These bar-magnets are connected at their upper part by means of the pin *i* which passes through the side plates and through the core *b* of the electro-magnet which is made hollow for the purpose.

As will be obvious machines made as above described are of less weight and occupy less space than one in which permanent magnets are provided both for illumination and ignition purposes. Furthermore, it will be understood that since the power of the field obtained from an electro-magnet is higher than that of a permanent magnet, the im-

proved machine may be utilized for starting an internal combustion engine, for which purpose the illuminating armature would be used as a motor for directly driving the crank-shaft of the engine.

70

I claim:

1. In a magneto electric machine for combined ignition and illuminating and starting purposes, the combination with a permanent magnet, provided with poleshoes adapted to receive a rotatable armature for generating ignition current, and an electromagnet provided with separate poleshoes located within and supported by the permanent magnet and its poleshoes, said electromagnet being adapted to receive a separate rotatable armature between the poleshoes thereof for generating a lighting current.

75

2. In a magneto electric machine for combined ignition and illuminating and starting purposes, the combination with a permanent magnet provided with poleshoes adapted to receive an ignition armature, an electromagnet comprising side plates located between the arms of the permanent magnet and provided with poleshoes supported above the poleshoes of the permanent magnet, and adapted to receive a rotatable armature for generating lighting current, and a coil supported between said side plates.

90

3. In a magneto electric machine for combined ignition and illuminating and starting purposes, the combination with a permanent magnet provided at its lower ends with poleshoes adapted to receive a rotatable armature for generating ignition current, an electromagnet comprising a pair of side plates mounted within the arms of the permanent magnet and provided with poleshoes adapted to receive a rotatable armature for generating lighting current, said poleshoes being supported above the poleshoes of the permanent magnet and extending above the same at each end, and being provided with downwardly extending supporting portions at each end of said poleshoes for the permanent magnet, said downward extensions being separate from the poleshoes of the permanent magnet to effect a partial magnetic insulation therefrom, and a magnetic coil supported within the side plates above the poleshoes for the electromagnet.

100

4. In a magneto electric machine for combined ignition and illuminating and starting purposes, the combination with a permanent magnet having vertically disposed portions provided at their lower ends with a pair of opposed poleshoes adapted to receive between them a rotatable armature for generating ignition current, and an electromagnet arranged between said vertically disposed portions of the permanent mag-

net and comprising two side plates provided at their lower ends with opposed poleshoes adapted to receive between them a rotatable armature for generating lighting current, said latter poleshoes being supported upon the poleshoes of the permanent magnet and connected thereto, and a magneto electric coil secured between said side plates above the poleshoes for the electromagnet, and supported by said side plates, the poleshoes for the electromagnet being of greater length than those for the permanent magnet,

and being provided at each end with downwardly extending supporting portions located at opposite ends of the adjacent poleshoes of the permanent magnet and separated therefrom by vertically disposed slots to provide for a partial magnetic insulation between said pairs of poleshoes.
